BOAT ANCHOR HOIST

Robert Ellis, Solana Beach, Calif., assignor to
 Robert E. Peterson, Downey, Calif.
 Filed Jan. 7, 1965, Ser. No. 424,024
 13 Claims. (Cl. 114—210)

This application is an improvement over my prior application Serial No. 397,192.

This invention relates to boat anchor hoists and the principal object of the invention is the provision of means for keeping the deck of the boat clear of the usual anchor and attached rope by hauling the anchor and rope below deck, all with a single manipulation of the anchor rope from any prescribed location on the boat.

Other and further objects will appear in the specifications and be specifically pointed out in the appended claims, reference being had to the accompanying drawings exemplifying the invention in which;

FIG. 1 is a top view of the mechanism while the anchor is being cast out or hauled in.

FIG. 2 is a longitudinal section of FIG. 1 on the line 2—2 thereof.

FIG. 3 is an isometric diagram of the integral extending arms and rotatable shaft.

Referring to the drawings in which like characters and numerals of reference refer to similar parts throughout the several views, the numeral 7 denotes the bow of the boat 6 and 8 is the deck thereof. A pilot house 9 may or may not be included on the boat, a combined steering wheel and reel 10, such as described in my Patent #3,068,828, being preferably located therein. A short transverse shaft 12 is located at the bow of the boat below deck 8, this shaft being rotatably mounted between bearings 11, comprising two angles as illustrated. Welded at right angles to shaft 12 is the vertically disposed pulley arm 15 and at right angles to pulley arm 15 is welded the horizontally forwardly disposed anchor arm 14, this anchor arm 14 being preferably slightly longer than pulley arm 15, with the anchor arm extending a short distance, slightly more than half the width of the circular anchor fluke 24, beyond the tip of the bow 7 of the boat 6. At the overhanging end of arm 14 is the elongated hole 21, which hole not only permits passage of anchor rope 23 therethrough but also the anchor shank 22 up to the hilt of circular fluke 24 of the anchor. A rope pulley 25 is rotatably mounted to the extending end of pulley arm 15 by means of shaft 13 as shown. It is thus apparent that the shaft 12, pulley arm 15, anchor arm 14, pulley 25 and pulley 40, all rotare together at all times as an integral part, this being better illustrated by the isometric diagram in FIGURE 3.

When in its upright position, pulley arm 15 extends vertically through the forward part of door opening 26 in deck 8, as better illustrated in FIG. 2, a suitable door 37, hinged at its rear side 28, closes this opening automatically when the anchor is pulled below deck 8 and opens it automatically when the anchor is cast out. A flat spring 38, attached to the underside of door 37 assists in accomplishing this action as indicated by the curved dotted lines. The open door is shown leaning by gravity against the pilot house but it is apparent that various known fittings may be used to hold the door in secure open position until the incoming anchor causes it to close. A fixed rope pulley 27 is rotatably mounted to that part of the boat 6, below deck 8, where it is desired to have the tip of the anchor shank 22 rest when the anchor is hauled into the boat. A pulley 40 is also secured to rotatable shaft 12, one end of the wire rope 41 being attached to the circumferential edge of pulley 40 at 42 while the other end of rope 41 is attached to helical spring 43 at 44, the other end of helical spring 43 being attached to loop 45

2

attached to any convenient place inside of boat 6. A pin 60 depends from anchor arm 14, this pin automatically fitting into socket 61, which is sunk into the tip of the bow 7 of the boat, when the anchor is cast, thus preventing side strain on the arm 14 due to yawing of the anchored boat due to wind and waves. It will be particularly noted that horizontally extending anchor arm 14 is welded to pulley arm 15 above deck 8 while in anchor casting position, thus creating an offset around shaft 12 and causing the arm 14 to swing below the deck 8 at a half revolution of shaft 12 in the direction of arrow 70 as indicated by the dotted lines.

The operation of this anchor mechanism is as follows: the full lines in the illustrations indicate the anchor in

15 the process of manipulation either during casting out or hauling in while the dotted lines show the anchor and mechanism stowed under the deck with the door 26 in closed position overhead and the deck 8 completely clear of the customary cluttering up of the anchor and anchor 20 ropes, leaving the deck for the unobstructed use of passengers or work of any kind. As here indicated, the rope 23 is being pulled in the direction of arrow 34 onto the reel 10 in pilot house 9. The tip of anchor shank 22 has already arrived at the outer tip of projecting anchor arm 25 14 and the shank 22 of the anchor is about to enter elongated hole 21, following rope 23 and beads 46 and to be pulled into position indicated by dotted lines 24B, the elongated hole 21 permitting some angular positioning of shank 22, the slight tension still existing in helical spring 30 43 tending to keep anchor arm 14 in horizontal position until the circular anchor fluke 24 contacts the end of anchor arm 14, whereupon the anchor arm is caused to describe the circular arc 50. Towards the end of its travel, the edge of the circular fluke 24 will contact the 35 protruding upper end of flat spring 38 attached to underside of door 37, the anchor now being illustrated at position shown by dotted lines 24C. The flat spring 38 will bend downward slightly as shown by dotted lines and yet be sufficiently rigid to cause the cover 37 to tip forward 40 and descend, and cover opening 26 as indicated by dotted lines and the arc 51. The anchor has thus been pulled completely into and through hole 26 and now occupies the upside-down position indicated by dotted lines 24D, the fluke resting in an upside-down position at the end of horizontally disposed anchor arm 14 while pulley arm 45 15 is in a vertical position extending downwards from slot 12 as shown. This action has taken place under continuously increasing tension of helical spring 43, due to the partial revolution of wire rope pulley 40. However, 50 due to the pawl 32 contacting ratchet teeth 31, attached to reel 10, the anchor remains in place without further pull on rope 23.

In order to cast the anchor into the water, the reverse motion takes place, the operator merely lifting the pawl 32 from teeth 31 thus causing the tension of spring 43 to rotate shaft 12 one-half revolution, lifting the anchor through arc 50, the circular edge of the anchor fluke 24 contacting underside flat spring 38 during this process and first opening door 37 into position shown, before dropping into the water, the pulley 25 also contacting rope 60 23, and finally assuming position shown by full lines, the rope 23 also unwinding from reel 10 as required.

It will be apparent that, in order to accomplish the foregoing operation successfully, all the components, such as the hollow anchor shank, which enables the anchor 65 rope to be secured to the anchor therein, the rounded tip of the anchor shank 22, the beads 46, the integral quadrant arms 14 and 15, the offset arm 14 in relation to the below deck transverse shaft 12, and the manipulation of the cover 37 by anchor fluke 24, all combine to create the practical operation of this mechanism.

While I have illustrated the anchor rope 23 being manually wound upon a reel, it will be understood that an electric motor and controls may be used such as illustrated in my previous patent application, Serial #397,192, in FIG. 8, or the end of the rope 23 may be simply wound around a cleat against the tension of helical spring 43 and tied, the loosening of this rope therefrom causing the anchor to be cast into the water as previously described, the door 37 being simultaneously manipulated automatically.

From the foregoing description it will be apparent that I have evolved a boat anchor and manipulating means therefor which will operate automatically by merely pushing a button or turning a wheel or loosening a rope, leaving the deck free and clear of the usual anchor and anchor ropes and enabling the deck to be used for the enjoyment of passengers or to more effectively do work thereon as well as to eliminate the individual labor of handling the anchor.

Various changes may be made in the embodiment of the invention hereinabove specifically described without departing from or sacrificing the advantages of the invention as defined in the claims appended hereto.

I claim:

1. In a boat anchor hoist, a boat having a deck, an opening in the deck at the bow of the boat, an anchor hoisting means attached to said deck at the forward part of said deck opening, an anchor and an anchor rope, one end of said rope being attached to said anchor, means for exerting pull to the other end of said anchor rope, said pulling means onto said rope causing said anchor and said anchor hoisting means to rotate in an arc of 180 degrees and both said anchor and said anchor hoisting means be deposited through said opening in said deck below the surface of said deck in said boat, and a cover for said deck opening, means on said cover for actuating said cover by said hoisting mechanism, the operation of depositing said anchor through said deck opening simultaneously actuating said cover into a closed position over said deck opening.

2. In a boat anchor hoist as in claim 1, and a spring attached to said anchor hoisting means, said spring being caused to increasingly load as said anchor is swung through said arc of 180 degrees by the pull of said rope, means for retaining said rope taut against the reverse pull of said spring, and means for releasing said rope retaining means to cause said anchor hoisting means to reverse its previous motion by the tension of said spring and cast said anchor into the water and simultaneously open aforesaid cover over said deck opening to permit said anchor and hoisting means to pass therethrough.

3. In a boat anchor hoist as in claim 1, the said anchor hoisting mechanism comprising a short transverse shaft rotatably mounted underneath the deck at the forward edge of said deck opening, a vertically disposed pulley arm attached to said transverse shaft the major part of said vertical arm extending through said deck opening when said anchor is cast out, a rope pulley at the upper end of said pulley arm, and a horizontally disposed anchor arm, one end of said anchor arm being rigidly attached to said pulley arm flush with the upper surface of said deck and the other end thereof extending partly over the prow of the boat, an elliptical opening at the extended end of said anchor arm, said elliptical opening being adapted to pass the said anchor rope therethrough and to receive the shank of said anchor up to the fluke thereof when said anchor is being hauled aboard, a spring, said spring being continuously tensioned to cast the anchor overboard, the said rope also passing over said pulley to a pulling means and causing said transverse shaft to swing in an arc of 180 degrees against the tension of said spring when said anchor is hauled aboard, the said anchor hoisting mechanism by virtue of its offset position in relation to said transverse shaft being caused to pass through said deck opening together with said anchor in an upside-

down position and to simultaneously actuate said cover into a closed position over said deck opening.

4. In a boat anchor-hoist, an anchor having an upstanding shank, an anchor rope, a reel, one end of said anchor rope being attached to said anchor shank and the other end of said rope attached to said reel, means for rotating said reel, an opening in said deck at the bow of a boat, a hinged door covering said opening, a short transversely mounted rotatable shaft below said deck at the forward edge of said deck opening, a vertically disposed pulley arm, a horizontally disposed anchor arm having its inboard end attached to said pulley arm flush with the deck of said boat and being provided with an elongated hole sufficiently large to pass said anchor rope and anchor shank therethrough to the fluke of said anchor, a rope pulley attached to said short transverse shaft, a helical spring, a rope connection between said rope pulley and one end of said helical spring, and means for attaching the other end of said helical spring to the inside of said boat, the said helical spring being under continual tension and adapted to project said anchor upwards through said deck opening, automatically opening said hinged door and casting said anchor into the water when the said reel is permitted to unwind.

5. In a boat anchor-hoist as in claim 4, the said anchor arm being attached at right angles to said pulley arm between said transverse rotatable shaft and said pulley thereon to cause said anchor arm to swing below the deck through said deck opening when said rotatable transverse shaft is rotated 180 degrees towards the rear of the boat.

6. In a boat-anchor-hoist as in claim 4, the said hinged cover for said deck opening being provided with means for contacting the said anchor when said anchor is hauled into the boat through said opening and to automatically close said cover over said opening as said anchor is fully retracted, and to automatically open said cover when said anchor is cast overboard.

7. A boat anchor hoist with means for manipulating same at a distance from the bow of the boat, a deck on the bow of the boat, an anchor having a hollow shank, an anchor rope, one end of said rope being adapted to enter the hollow shank and being attached to said anchor, a short shaft, bearings for said shaft, the said shaft being mounted transversely close below said deck near the tip of the bow of the boat, an opening in said deck, said opening extending aft of said shaft mounting, a vertically extending pulley arm having one end thereof permanently attached to said transverse shaft, a pulley at the other end of said vertically extending pulley arm, a horizontally disposed anchor arm, said anchor arm having one end thereof permanently attached to said vertically extending pulley arm while the other end thereof extends outboard over the bow of the boat, a helical spring, a pulley attached to said short transverse shaft, one end of said helical spring being attached to a convenient inner part of said boat while the other end of said spring is attached to said pulley and adapted to continually exert tension thereon to hold said anchor arm in an outboard position downward over the bow of said boat, a reel, one end of said anchor rope being attached to said reel, means for rotating said reel and retaining said rope against unwinding from said reel, a pulley attached to the inside of said boat below said deck opening, a hinged door over said opening, the other end of said rope passing over said pulley and the pulley at the end of said pulley arm and through a chamfered hole at the outer end of said anchor arm to said anchor, the said anchor being adapted to be pulled into said opening and to automatically close said hinged door as said anchor is being hauled through said opening by a pull on said rope.

8. A boat anchor hoist as in claim 7, the shank tip terminating at the aforesaid inside pulley when said anchor is fully hauled into the boat.

9. A boat anchor hoist as in claim 4, and a socket, a pin adapted to snugly fit into said socket the said socket

being recessed vertically into the prow of the boat directly underneath the anchor arm when said anchor arm is extending outboard and the said depending pin being secured to the lower side of said anchor arm and adapted to register with said socket when said anchor arm is flush with the deck.

10. An anchor hoist adapted to be mounted below the deck of a boat at the bow of the boat, an opening in the deck adjacent the said hoist, a hinged cover for said opening, the said anchor hoist comprising a horizontally disposed rearwardly extending anchor arm pivoted at the forward end thereof under normal anchor retracted position, said pivot being at the forward edge of said deck opening, said anchor arm being provided with an aperture at its extreme rearward end for the passage of an anchor rope and the reception of an anchor shank up to the fluke thereof and adapted to hold said anchor downward in an upside-down position by said anchor rope against the tension of spring means, the loosening of said anchor rope permitting said spring means to cause said rearwardly extending horizontally disposed anchor arm below said deck to swing in an arc of 180 degrees to a forwardly overboard extending horizontal position and cast said anchor into the water beyond the prow of said boat.

11. An anchor hoist as in claim 10, the said 180 degree traverse of said anchor simultaneously contacting the

underside of said hinged cover over said deck opening and causing said cover to remain open until said anchor is hauled into the boat by a reverse motion of said mechanism by means of pulling said anchor rope into said boat and causing said anchor to close said cover over said deck opening as said anchor is pulled below deck.

12. An anchor hoist as in claim 10, and a vertically disposed pulley guide arm, one end of said pulley arm being irremovably attached to said anchor arm at the pivot thereof.

13. In a boat anchor hoist as in claim 4, the said anchor arm and the said pulley arm being permanently attached at right angles to each other and adapted to swing in unison and alinement with each other together with said transverse shaft.
